DRAFTING INSTRUMENT

Louis Veyret, Neuilly-sur-Seine, and Georges Gefroy, Paris, France, assignors to La Cellophane, Paris, France, a French company

Application February 26, 1948, Serial No. 11,246
In France June 6, 1945

Section 1, Public Law 690, August 8, 1946
Patent expires June 6, 1965

3 Claims. (Cl. 33—79)

1

This invention relates to drafting instruments of the type having a head carrying two mutually perpendicular rules and supported by a system of deformable parallelograms, permitting the combination of rules to be displaced parallel to themselves over the entire extent of the drawing board, while the rules themselves may be angularly adjusted and set in various selected positions with reference to their support.

The invention relates particularly to a drafting instrument head, i. e. a linkage mechanism between the rules and their deformable support. The invention provides a knob rotatably mounted about a vertical axis on a cylindrical bearing fixed to the system of rules, and acting, first, on a brake mechanism permitting fixed adjustment of the system of rules in various desired positions upon its support; and, second, upon a lock working in conjunction with corresponding holes in the support to permit the system of rules to be locked in a series of predetermined angular positions.

Other features of the invention will be apparent from the following description taken in connection with the accompanying drawings in which certain specific embodiments are set forth for purposes of illustration.

In the drawings:

Fig. 1 is a vertical section showing one form of drafting instrument head embodying the invention;

Fig. 2 is a vertical section showing another embodiment of the invention;

Fig. 3 is a partial bottom plan view of the device shown in Fig. 2;

Figs. 4 to 6 are vertical sections showing other embodiments of the invention;

Fig. 7 is a partial top plan view of the device of Fig. 6; and

Fig. 8 is a diagrammatic view showing the device applied to a drawing board.

In reference to the drawings, and in the figures as a whole, 1 designates the support for the movable head, which is shiftable over the drawing board by means of parallelogram links as shown in Fig. 8. A set of rules are carried by a head 2 pivoted to the support 1. An operating knob 3 is rotatably mounted on a bearing 4 fixed to the head 2. A brake rod 5 carries a shoe 6 and is supported by a nut 7 engaging threads 8 cut on knob 3. A plunger 9 ends in a conical tip and carries a projection 10 resting on a helical groove 11 on the knob 3. 12 is a retaining spring for the plunger 9 which engages conical holes 13 in the support 1 located on the periphery of a circular arc.

2

In Fig. 1 the head 2 is located above the support 1, and the plunger 9 slides in a coaxial bore in the bearing 4, in which it is keyed to slide without rotation. The groove 11, ending in a horizontal portion 14, is accommodated in the internal wall of the knob 3, the bearing 4 being recessed to receive the projection 10. The knob 3 is held in vertical position on the bearing 4 by spurs 15 engaging a horizontal slot in the bearing 4. The threads 8 are cut on the outer wall of the knob 3, and the nut 7, coaxial with bearing 4, knob 3 and plunger 9, surrounds the knob 3. The rod 5, attached to the nut 7 by threads 16 is displaced laterally with respect to the knob 3. When the nut 7 rises, the shoe 6 bears with its upper face upon the lower face of the edge of the support 1. The screw pitch of threads 8 is such that when the knob 3 is turned clockwise, the nut 7 is lowered, taking with it the rod 5, the groove 11 being such that the plunger 9 likewise descends in the same motion.

In the position of Fig. 1, the brake is off and the plunger 9, engaging a hole 13 and retained by its spring 12, locks the movable portion 2 to the support 1 in a position determined by the location of the hole 13. If it is desired to displace and set the movable portion 2 into some position between two of the holes 13, the knob 3 is turned counterclockwise. The projection 10 then rises on the groove 11, and the plunger 9 is raised until the projection 10 reaches the horizontal portion 14 of the groove. In this motion, the plunger 9 is withdrawn from the hole 13, thus releasing the movable portion 2, and the rod 5 is raised slightly, though without making contact between the shoe 6 and the support 1. The movable portion 2 is thus free and may be turned to the desired position. To keep it in that position, the knob 3 is further turned counterclockwise, the projection 10 thus passing over the horizontal portion 14 of the groove. The plunger 9 remains in disengaged position, the rod 5 continues to rise, and the shoe 6 is brought to bear against the support 1, thus securely clamping the movable portion 2 to the support 1.

In Figs. 2 and 3, the mechanism is the same as in Fig. 1, but the rod 5 is coaxially placed in the interior of the plunger 9, and the nut 7 is permanently tightened and locked in the interior of the knob 3. When the knob 3 is turned, the rod 5 is screwed or unscrewed, as the case may be, in the nut 7, which as aforesaid turns with the knob 3. The holes 13 are formed partially in the support 1 and partially in a part 17 fixed to the movable portion 2 (see Fig. 3). The vertical

guidepin 18 of the lock 9 is displaced in a vertical groove 19 in the bearing 4, in such a manner as to prevent any rotation of the plunger 9.

Operation is the same as in Fig. 1.

In Fig. 4, the movable portion 2 is placed below the support 1 and the operating mechanism is mounted on a bracket 20 fixed to the movable portion 2 and surmounting the support 1. The rod 5 is coaxially placed in the interior of the bearing 4 supporting the knob 3, and the plunger 9 slides on the exterior of the knob 3 in a cylindrical part 21 fixed to the bracket 20. The projection 10, which moves in a notch in the part 21, acts upon a lever 22 pivoting on a shaft 23 in a bearing 24 fixed to the bracket 20, the free end of the lever 22 resting in turn upon the cam surface 11 on the external wall of the knob 3. The tension spring 12 is attached at one end to the bracket 20 and at the other end to the projection 10.

Operation is the same as in the preceding case.

In Fig. 5 the mechanism is substantially the same as in Fig. 4, with the difference that the movable portion 2 is above the support 1, as in the case of Figs. 1 to 3. The lever 22 is omitted, and the plunger 9 carries a follower 25 acting directly on the cam surface 11.

It will be noted that in the case of Figs. 1 to 5, the plunger 9 may readily be removed and omitted, in which case the mechanism may be set by the brake alone.

The mechanism of Figs. 6 and 7 is analogous to that of Figs. 2 and 3, but the rod 5 is elevated simply by the rising of the plunger 9, the rod 5 not being connected to the knob 3 and having a head 26 which may be brought to rest on a shoulder 27 in the upper part of the plunger 9. A weak spring 28 retains the rod 5 upward. The horizontal portion 14 of the incline is extended to form a second helical groove 29. The holes 13 are entirely accommodated in the support 1, being joined by a slot 30 to pass the rod 5 (Fig. 7), the two portions of the slot 30 being connected below by an annular channel 34 with a U-shaped cross section to accommodate the shoe 6.

In turning the knob 3 counterclockwise, an initial upwards motion of the plunger 9 is produced, thus withdrawing it from the hole 13 and compressing the spring 28. In the horizontal portion 14 of the incline, the movable portion 2 is free, whereupon the additional rise of the projection 10, when the latter follows the groove 29, lifts the rod 5 by its head 26 on the shoulder 27 and clamps the shoe 6 against the support 1.

Naturally, the invention is not restricted to the specific forms illustrated and described, which have been selected by way of example. The in-

vention is only to be limited in accordance with the scope of the following claims.

What is claimed is:

1. In a drafting instrument of the type comprising a support mounted to move over a board and a head carrying a rule pivoted to said support, adjusting and locking mechanism for said head comprising a base plate having an arcuate row of holes fixed to said support, a sleeve fixed to said head, a plunger slidable vertically in said sleeve and adapted to enter a selected hole, a bearing member mounted on said head, a knob journaled on said bearing member to rotate about a vertical axis, said knob having a helical cam surface, a cam follower connected to ride on said surface for elevating said plunger, said surface terminating in a horizontal portion so arranged that initial turning of the knob lifts the plunger and further turning of the knob retains the plunger elevated, a brake mechanism comprising a rod slidably mounted on said head and carrying a brake shoe to clamp against the under surface of said base plate, a nut carrying said rod and said nut being concentric with and threaded to said knob and being fixed against rotation so as to be raised or lowered by turning of the knob, the threads on said nut having a pitch such that rotation of the knob in a direction to raise said plunger and to a position corresponding to the horizontal portion of said cam surface also applies said brake.

2. A drafting instrument, as set forth in claim 1, in which the plunger is mounted coaxially with said knob.

3. A drafting instrument, as set forth in claim 1, in which said cam surface comprises a groove on the inner surface of said knob and said cam follower comprises a pin attached to said plunger and engaging said groove.
